[57] **CLAIM**

The ornamental design for a hanger unit for cable or similar articles.

DESCRIPTION

FIG. 1 is a perspective view of a hanger unit for cable or similar articles showing my new design, it being understood that the fiber pattern is repeated throughout the circumference of the fiber hanger, as shown schematically by solid lines, the opposite side being substantially a mirror image of that shown;

FIGS. 2 and 3 are respectively left side and bottom perspective views of the hanger unit, it being understood that the fiber pattern as shown is repeated throughout the circumference of the fiber hanger.
